UNITED STATES PATENT OFFICE.

ROBERT K. DAWSON, OF AKRON, NEW YORK.

HUB FOR CHAIR BASES.

Application filed April 12, 1924. Serial No. 706,207.

To all whom it may concern:

Be it known that I, ROBERT K. DAWSON, a subject of the King of Great Britain, residing at Akron, in the county of Erie and State of New York, have invented a new and useful Improvement in Hubs for Chair Bases, of which the following is a specification.

This invention relates to chair bases and particularly to the hub portions thereof to which the legs of the chair are secured.

The objects of this invention are to provide a hub for a chair base of strong and rigid construction, which is made mainly of sheet metal or stamped parts; also to provide a chair base hub of this kind including upright parts which are spaced apart to form between them wedge shaped recesses into which the ends of the legs of the chair may be driven for securely holding the legs in their correct relation to the chair base; also to provide a construction of this kind in which the central tube or sleeve of the hub member is utilized for securing all of the parts of the hub together; also to improve the construction of hubs for chair bases in other respects hereinafter specified.

In the accompanying drawings:

Fig. 1 is a fragmentary sectional elevation, on line 1—1, Fig. 2, of the hub of a chair base embodying the invention.

Fig. 2 is a horizontal section thereof on line 2—2, Fig. 1.

Fig. 3 is a side elevation of the hub of the chair base on a reduced scale.

Fig. 4 is a fragmentary bottom plan view thereof.

Fig. 5 is a bottom plan view thereof with the chair legs and the lower leg securing plate omitted.

Fig. 6 is a top plan view thereof.

Fig. 7 is a detached plan view of a plate for holding the lower ends of the gripping leg or wedge bars in place.

Fig. 8 is a perspective view of the lower end of one of the leg gripping or wedge bars.

Fig. 9 is a fragmentary detailed view on line 9—9, Fig. 5.

A represents the upper ends of the usual legs of the chair which are generally made of wood and which extend radially from the hub portion of the chair base, and B represents a central tube or sleeve through which the usual chair spindle or screw stem (not shown) extends. This invention deals particularly with the means for securing the

chair legs rigidly in their operative relation to the central tube or sleeve, or to any other form of central or hub member.

The chair hub includes a plurality of leg gripping or wedge bars which extend substantially lengthwise of the hub and which are spaced apart to form between them dove-tailed recesses into which the inner ends of the legs are adapted to enter. These bars are represented by C and are preferably in the form of sheet metal strips having their sides bent at an obtuse angle to each other so that the oppositely disposed sides of two of these bars converge toward each other outwardly from the axis of the hub of the chair base. The inner ends *a* of the chair legs are dove-tailed so as to fit between the adjacent sides of these leg gripping bars, and the leg gripping bars are preferably spaced farther apart at one end than the other end and the ends *a* of the leg are preferably also slightly wedge shaped, being made of slightly greater thickness at the lower portions thereof than at the upper portions. In the construction shown the lower ends of the bars are spaced farther apart than the upper ends and consequently when the inner ends of the legs are driven upwardly into the spaces between the adjacent sides of the leg gripping bars, these ends of the legs will be tightly wedged into their operative positions and will be firmly held in place. Shoulders *a'* are formed on the legs A at the juncture of the dove-tailed portions *a* of the legs with the body portions thereof, which shoulders engage with the outer edges of the bars C to limit the extent to which the dove-tailed portions of the legs enter the recesses between adjacent bars. In order to hold these leg gripping bars in proper relation to each other, the following construction is preferably employed.

The upper ends of the leg gripping bars may be secured in any suitable manner to an upper plate D of the hub. In the particular construction shown in the drawings for this purpose, each of the two sides *c* of the leg gripping bars is provided at its upper end with an extension or projecting portion *c'* which is adapted to extend through a corresponding hole or slit in the top plate D. If desired, the upper extremity of each of the projections *c'* may then be riveted or turned over so as to prevent the disengagement of the upper ends of the leg gripping bars from the top plate D.

- Any other means for holding the upper ends of the leg gripping bars in correct relations to the top plate may be provided, if desired.
- 5 The lower ends of the leg gripping bars are preferably secured to a lower bar holding plate E, which in the construction shown is substantially square, see Fig. 7, and is provided with a central bore or opening 10 e through which the lower end of the central tube or sleeve B is adapted to extend, and recesses or notches e' are preferably provided in this plate for the purpose hereinafter specified. This plate must be considerably smaller than the upper plate D in order to permit the inner ends of the legs A to pass the edges of this plate as the legs are moved toward the upper plate D between the sides c of the leg gripping bars 15 20 25 30 35 40 45 50 55 60 65 70 75 80 85 90 95 100 105 110 115 120 125 130
- C. In order to interlock with the lower bar securing plate E, the lower end of each of the leg gripping bars is preferably provided with an integral, radially extending portion F, the outer end of which has a claw or shouldered part f which may be made by bending the outer end of the extension F downwardly, as is clearly shown in Figs. 1 and 8. The claws or shouldered portions f are adapted to enter into the recesses e of the lower bar engaging plate and the faces f' of the extension F, which are arranged nearest to the axis of the hub are adapted to engage the central tube or member B.
- The lower bar engaging plate E may be held in operative relation to the lower ends of the bars in any suitable or desired manner. In the construction shown for this purpose, the lower end of the central tube or sleeve B is turned outwardly in any suitable or desired manner, as indicated at G, so as to engage the lower bar securing plate E and hold the same in operative relation to the bars C, and the turned-over portion G also engages the outer ends of the shouldered portions f of the bars to hold the same rigidly in place, as well as pressing the lower plate against the lateral extensions of the bars. The upper end of the central tube or sleeve B may be secured to the upper plate D in the same manner, namely by turning over the upper end of this central tube or sleeve, as indicated at G'. By means of this construction the turned-over ends of the central tube or member securely hold all of the parts of the chair base hub together and thus form a rigid and very secure structure. The radially extending portions F of the lower leg gripping bars are made of such lengths that the lower ends of the bars extend to a slightly greater distance from the sides of the central tube or sleeve than the upper ends of these bars, thus forming wedge shaped recesses between the adjacent legs or flanges of each of these bars, and the inner ends a of the legs are driven into these wedge shaped recesses, thus forming a very secure connection between the hub portions of the chair base and the legs, while the dove-tailed shapes of the recesses prevent the inner ends of the legs from moving out of the recesses. The edges of the bars engage the shoulders a' formed on the legs near the inner portions thereof so that any movement of the legs relatively to the hub of the base is prevented.
- A lower leg securing plate H may be used in connection with the hub of the chair base, if desired, and in the construction shown this lower plate is provided with an opening h in the central portion thereof, preferably of such shape as to permit the lower bar securing plate E to extend into the opening thereof, as shown in Figs. 1 and 4. This lower leg securing plate has laterally extending arms h' of usual construction. This plate and the arms h' thereof are provided with a plurality of holes through which screws may pass which enter into the lower faces of the legs A and serve the usual function of strengthening the base of the chair. The legs are preferably also provided with the usual recesses h arranged beyond the edges of the leg gripping bars C and into which the sides of filler pieces K may enter, which conceal the securing means which hold the legs together and give the chair base a finished appearance.
- I claim as my invention:
1. A hub for a chair base including a plurality of leg gripping bars of angle shaped cross section spaced apart to form between them recesses to receive the chair legs, a plate to which one end of each of said bars is rigidly secured, another plate having recesses adapted to receive portions extending from the other ends of said bars, and a central member secured to said plates and holding said other plate in a position in which said portions of said bars are retained in said recesses.
  2. A hub for a chair base including a plurality of leg gripping bars of angle shaped cross section spaced apart to form between them recesses to receive the chair legs, a plate to which one end of each of said bars is rigidly secured, another plate having recesses adapted to receive portions extending from the other ends of said bars, and a central tubular member having its opposite ends turned over against said plates to press said plates against said bars for holding said portions of said bars in the recesses of said other plate.
  3. A hub for a chair base including a plurality of leg gripping bars of angle shaped cross section spaced apart to form between them recesses to receive the chair legs, plates arranged at the opposite ends of said bars, one end of each bar having in-

tegral projecting portions adapted to extend through holes in one of said plates and peined over to secure said bars to said plate, the other ends of said bars having radially 5 extending portions adapted to lie substantially flatly against said other plate and having shouldered end portions adapted to enter into recesses in said other plate, and a central tubular member having its ends 10 turned over against said plates to press said plates against the ends of said bars and to hold said shouldered portions of said bars in said recesses of said other plate.

4. A hub for a chair base, including a 15 central member, a plurality of leg gripping bars, means for securing one of the ends of each of said bars in fixed relation to said central member, a plate having an aperture through which one end of said central member 20 extends, and which is provided with recesses, projecting portions on the other ends of said bars extending into said recesses, and means on said central member 25 engaging said plate and the ends of said projecting portions of said bars for holding said plate in operative relation to said other ends of said bars to hold said projecting portions in said recesses.

5. A hub for a chair base including a 30 central member, a plurality of leg gripping bars, means for securing the upper ends of said bars in fixed relation to said central member, a plate having an aperture through which the lower end of said central member 35 extends and which is provided with recesses, the lower ends of said bars having radially extending portions adapted to engage said plate and shouldered end portions adapted to enter into said recesses to hold said bars 40 in definite relation to said plate, said radially extending portions serving to limit the extent to which said shouldered end portions may be inserted into said recesses and means for securing said plate to said central member to hold said plate in fixed relation to said bars.

6. A hub for a chair base, including a 45 central member, a plurality of leg gripping bars spaced apart, the adjacent sides of each pair of bars forming a recess adapted to receive the end of a chair leg, means for securing the upper ends of said bars in fixed relation to said central member, a plate hav-

ing an aperture through which the lower end of said central member extends and 55 provided with recesses, the lower portions of said bars being provided with integral inwardly extending portions adapted to lie flatly against said plate, the ends of said radially extending portions being bent to 60 enter into said recesses, and means on said central member for holding said plate against said radial portions of said bars to retain the bent ends thereof in said recesses.

7. A hub for a chair base, including a 65 central tubular member, a plurality of leg gripping bars spaced apart, the adjacent sides of each pair of bars forming a recess adapted to receive the end of a chair leg, means for securing the upper ends of said 70 bars in fixed relation to said central member, a plate having an aperture through which said central member extends and having laterally extending recesses adjoining said apertures, integral radially extending portions on the lower ends of said bars and 75 adapted to extend into said recesses, the lower end of said central tubular member being turned over to hold said plate in operative relation to the lower ends of said 80 bars and to hold said ends of said bars in said recesses.

8. A hub for a chair base, including a 85 central tubular member, a plurality of leg gripping bars spaced apart, the adjacent sides of each pair of bars forming a recess adapted to receive the end of a chair leg, the lower ends of said bars being arranged farther apart than the upper ends thereof to give said recesses a wedge shape, upper 90 and lower plates through which said central tubular member extends and provided with apertures, projections on the upper ends of said bars extending into apertures in the upper plate, and radially extending integral projections at the lower ends of said bars terminating in downwardly extending 95 portions which are adapted to enter into apertures in said lower plate, the upper and lower ends of said tubular member being turned over against said plates to hold said plates in position to press against the opposite ends of said bars and to prevent the projections of said bars from moving out of said recesses in said plate.

ROBERT K. DAWSON.
